UNITED STATES PATENT OFFICE

125,254

DESIGN FOR A SHOE

George H. Bingham, Jr., Cambridge, Mass., assignor to Cambridge Rubber Co., Cambridge, Mass., a corporation of Massachusetts

Application October 19, 1940, Serial No. 95,929

Term of patent 3½ years

To all whom it may concern:

Be it known that I, George H. Bingham, Jr., a citizen of the United States, residing at Cambridge, in the county of Middlesex and Commonwealth of Massachusetts, have invented a new, original, and ornamental Design for a Shoe, of which the following is a specification, reference being had to the accompanying drawing, forming a part thereof, in which

Fig. 1 is a side elevational view of a shoe showing my new design, the opposite side of which presents substantially the same appearance as the side shown.

Figure 2 is a rear end elevation of the shoe shown in Fig. 1.

My design is characterized by a platform shoe bottom, the platform section of which has a covering including a triangular portion at the rearward end thereof, as shown, contrasting in appearance with the adjacent portion.

I claim:

The ornamental design for a shoe, substantially as shown and described.

GEORGE H. BINGHAM, JR.
